(57) CLAIM

The ornamental design for a combined vanity table and chair, as shown and described.

DESCRIPTION

FIG. 1 is a front perspective view of a combined vanity table and chair, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front perspective view showing the combined vanity table and chair in an open state.

The broken lines in the drawings illustrate the portions of the combined vanity table and chair, which form no part of the claimed design.

1 Claim, 9 Drawing Sheets
